UNITED STATES PATENT OFFICE.

WILLIAM H. MORENUS, OF LAKEVIEW, IOWA, ASSIGNOR TO FREDERICK C. AUSTIN, OF CHICAGO, ILLINOIS.

GRADING AND DITCHING MACHINE.

SPECIFICATION forming part of Letters Patent No. 690,451, dated January 7, 1902.

Application filed November 5, 1900. Serial No. 35,522. (No model.)

To all whom it may concern:

Be it known that I, WILLIAM H. MORENUS, a citizen of the United States, residing at Lakeview, in the county of Sac, State of Iowa, 5 have invented a certain new and useful Improvement in Grading and Ditching Machines, of which the following is a specification.

My invention relates to grading and ditching machines, and more particularly to machines of the general construction illustrated by Letters Patent of the United States No. 275,614, dated April 10, 1883, and No. 636,506, dated November 7, 1899.

15 The more prominent objects of my invention are to relieve the forward bolster from draft strain, especially when the plow is working through hard soil, and to cause the tongue or pole to take the draft strain or back pull 20 of the draft-bar which carries the plow; to provide a simple and efficient construction and arrangement of means for the attainment of the foregoing-mentioned result; to permit the machine to turn or take a curved path 25 while the plow is at work without causing undesirable movement of the draft-bar and plow as a result of laterally swinging the tongue or pole; to provide means whereby the draft strain incident to the resistance of the 30 plow can be applied either to the tongue or pole or to the forward bolster at will, according to the character of the work, and to permit the adjustment of means employed for transferring the draft strain to the forward bolster to effect a forward adjustment of the 35 draft-bar to which the plow is attached.

In the accompanying drawings, Figure 1 is 40 a side elevation of a grading and ditching machine substantially involving the general construction shown in said Letters Patent No. 275,614, but understood to be modified in accordance with my invention. Fig. 45 2 is a top plan view, on a larger scale, of a portion of said machine, said view mainly comprising the draft-bar, plow-beam, and a portion of the forward running-gear with a draft connection between the draft-bar and the tongue or pole. Fig. 3 is a part section 50 and part elevation of Fig. 2, the draft-bar, forward bolster, axle, and forward portion of the hounds or draft-yoke being shown in sec-

tion on a substantially central longitudinal line through Fig. 2, the section-line forward of the hounds or draft-yoke being irregularly carried forward, so as to cut through the bolts. 55 by which one of the brace-bars is attached to the tongue or pole, it being observed that by this mode of illustration a multiplicity of more or less confusing section-lines is avoided and the invention more clearly shown. Fig. 4 is a 60 view similar to Fig. 3, but shows an adjustment whereby the draft strain is transferred from the tongue or pole to the forward bolster and the draft-bar adjusted forward relatively to the front bolster. Fig. 5 is a sectional detail of a portion of Fig. 3 on a larger scale, the section being on a vertical plane through a bearing-box fitted upon the front bolster.

The grading and ditching machine illustrated in said drawings comprises, among 70 other matters not necessary to be herein described, a suitable body-frame A, with front and rear supporting-wheels, a longitudinally-arranged plow-beam B, provided with a plow C and preferably positioned at one side of the 75 machine, a combined balance and draft bar D, pivotally connected at one end portion with any suitable part of or support upon the body-frame and at its opposite end portion attached to the plow-beam, and means such 80 as described in said patents or other suitable or desired means for raising and lowering the plow-beam. The machine further comprises a cable or draft-chain E or equivalent articulated draft connection, which is attached to 85 the draft-bar, and a tongue or pole F, suitably connected with the forward bolster G.

In a machine embodying my improvements the draft-chain E, which is attached to the horizontally-swinging draft-bar, takes the 90 draft from the tongue or pole F, so that during operation, and particularly when the soil is hard to plow, the draft strain incident to the connection of the chain with the draft-bar will be taken by the tongue or pole, thereby 95 relieving the forward bolster and its adjuncts from such strain and liability to breakage.

As a simple and effective connection between the draft-chain and the tongue or pole the latter is provided with a bar or plate H, 100 bolted to its under side and having its rear end extending back from the rear end of the

tongue or pole and adapted to form a hook I, with which the chain can be connected. With such arrangement an upwardly-bent plate 1 is secured to the tongue or pole and arranged 5 so that its rear portion shall overhang the rear portion of said tongue or pole and provide a bearing for a bolt 2, which also passes through a bearing-plate 3, secured to the tongue or pole, and through the forward portion of the hounds or draft-yoke K, the plate H, and the plate 4, preferably secured to the under side of the tongue or pole between the latter and the plate H, as illustrated by dotted lines in Figs. 3 and 4, it being observed that 15 the forward position of the draft-yoke K is clamped between said plates 3 and 4, and the hook I on the rear end of the plate H is also arranged so that the draft-line will be substantially through the longitudinal center of 20 the tongue or pole. By this arrangement a compact and strong arrangement for connecting the draft-chain with the tongue or pole is obtained and liability to rupture under the great strains to which the parts are subjected 25 will be avoided.

The transversely-arranged draft-bar D is arranged to have a suitable extent of horizontal swing, and hence when connected with the tongue or pole by the chain E the back 30 pull incident to the resistance of the ground to the plow will particularly be upon the tongue or pole.

As best illustrated in Fig. 5, the draft-chain comprises a rod 5, adapted to serve as a link 35 in said chain and arranged to pass and work through an opening 6 in the front bolster and corresponding openings 7 formed through the front and rear sides of a bearing box or casting L, through which the forward bolster G 40 and axle M are extended. This box or bearing G is also provided with rearwardly-extending portions 8, having bolt-holes, whereby connection can be made with the body-frame by means of a suitable king-bolt in any desired way, one of said bolt-holes being shown 45 in Fig. 2. The forward portion of the rod 5 is threaded and screwed into a nut 10, forming a part of one of the chain-links, whereby the relative adjustment between said link and 50 rod can be varied. The rod is also provided with a nut N, adapted for adjustment along the rod and arranged between the nut or link portion 10 and the forward bolster. When this adjustable nut or stop N is adjusted forwardly upon the rod, as in Fig. 5, the draft strain will be upon the tongue or pole; but by adjusting the nut or stop N rearwardly 55 and swinging the draft-bar forwardly to an extent to cause the portion of the chain to 60 drop slack when said nut or stop N bears against the front side of the box or bearing L, as in Fig. 4, the draft strain will be upon the forward bolster. If, however, it is now desired to set the draft-bar farther back, such

can be accomplished by operating a double 65 swivel-nut 11, arranged as one of the links of the chain.

What I claim as my invention is—

1. The combination in a grading and ditching machine of a wheel-supported body-frame; a longitudinally-disposed plow-beam provided with a suitable plow and arranged at one side of the machine; a transversely-arranged stay and draft-bar D attached to the plow-beam and hinge-connected with the wheel-supported body-frame; the forward bolster and a tongue or pole connected therewith; a draft-chain or cable connecting the draft-bar with the tongue or pole; and means for positively securing such chain or cable to the middle portion of the forward bolster, or releasing it from such positive connection with the forward bolster, at will, whereby the draft can be transferred from the pole to the forward bolster or from the latter to the former. 85

2. In a grading and ditching machine, the combination of a transversely-arranged draft and balance bar attached to the plow-beam and connected with a wheeled body-frame; a draft-chain or cable adapted to connect the draft-bar with the tongue or pole and including a threaded rod; a nut or stop adjustable along said rod and adapted when adjusted in one direction to connect the chain or cable with the bolster so as to throw the draft strain 90 thereon, and when adjusted in an opposite direction to relieve the bolster from such draft strain and permit the same to be taken by the tongue or pole, substantially as described. 95

3. A grading and ditching machine comprising a horizontally-swinging draft-bar connected with a longitudinally-arranged plow-beam; a draft-chain or cable arranged to connect the draft-bar with the tongue or pole 105 and including as one of its links a threaded rod; a front bolster and box or bearing thereon having guide-openings for the said rod; and a nut or stop applied for adjustment along said rod and arranged forward of the 110 front bolster, whereby, by adjusting the nut or stop forward, the draft strain will be on the tongue or pole, and by adjusting said nut or stop rearwardly, the draft strain will be taken by the front bolster, substantially as 115 described.

4. In a grading and ditching machine, the tongue or pole attached to the hounds or a draft-yoke; a chain or cable connecting the tongue or pole with a transversely-arranged draft-bar attached to a longitudinally-arranged plow-beam; and the front bolster and a box or bearing thereon provided with a guideway for a portion of the chain or cable. 120
